UNITED STATES PATENT OFFICE

ORVILLE M. DUNNING, OF EAST ORANGE, NEW JERSEY, ASSIGNOR TO THOMAS A. EDISON, INCORPORATED, OF WEST ORANGE, NEW JERSEY, A CORPORATION OF NEW JERSEY

COMBINED ELECTRICAL RECORDER AND REPRODUCER FOR PHONOGRAHS

Application filed April 11, 1931. Serial No. 529,385.

This invention relates to a combined electrical recorder and reproducer for phonographs such, for example, as dictating machines.

5 It is an object of this invention to provide an improved combination electrical recorder and reproducer which may be easily and simply operated by anyone without technical experience.

10 It is a further object of this invention to provide such a combination electrical recorder and reproducer in which the armature and the moving system generally may be made as small and light as possible.

15 It is a further object of this invention to provide a combination electrical recorder and reproducer which will operate satisfactorily with records of differing diameter such, for example, as may be encountered in

20 the use of business dictating machines where the records are shaved after use and used again and again.

It is a further object of this invention to provide a combination electrical recorder and reproducer which will have the optimum weight or pressure upon the stylus for both recording and reproducing and which will at the same time have high sensitivity.

The features of novelty which I believe to be characteristic of my invention are set forth with particularity in the appended claims. My invention itself, however, both as to its fundamental principles and as to its particular embodiments, will best be understood 35 by reference to the specification and accompanying drawings, in which.

Fig. 1 is a diagrammatic view of apparatus according to this invention in recording position;

40 Fig. 2 is a bottom plan view of the combined unit;

Fig. 3 is a detail side elevation on an enlarged scale, and

45 Fig. 4 is a side elevation showing the apparatus in reproducing position.

In my application, Serial No. 466,902, filed July 10, 1930, I have shown and described a combined electrical recorder and reproducer of the same general type as herein referred to.

50 In the said application there is utilized a

single combined unit operable either as a recorder or a reproducer and selectively movable from recording to reproducing position.

It was likewise pointed out therein that greater pressure should be applied against the stylus for reproducing than for recording and that this reduction of weight or pressure upon the stylus in recording position could be obtained by the use of an advance ball positioned upon the frame of the unit and traveling over an uncut portion of the record.

It was further pointed out that by varying the position of the advance ball with respect to the recording stylus the desired pressure or weight could be obtained upon the recording stylus regardless of the weight of the unit; that is to say, the desired proportion of the total weight of the unit supported by the stylus could be determined.

The present invention relates to the same general arrangement as already discussed, with which the change from recording to reproducing position is obtained by shifting the position of the unit, and also contemplates the supporting of the unit in recording position by means of an advance ball and the recording stylus, and in reproducing position by the reproducing stylus only.

In accordance with the present invention the advance ball is set alongside the recording stylus and is so adjusted or its height so chosen with reference to the recording stylus that said stylus engages the record before it is engaged by the advance ball. The height of the advance ball is so chosen that it comes into contact with the record when the recording stylus has penetrated a predetermined distance into the record. More specifically, if it is desired to have the stylus cut a groove of predetermined depth, the advance ball is made lower than the recording stylus by the depth of the cut desired.

Referring now more particularly to Fig. 1, 1 designates the combined recording and reproducing unit, the frame of which carries a pair of studs, 2 and 3 arranged to engage and hook into a depression in the extension 4 of arm 5.

The armature 11 carries a reproducing stylus 9 and a recording stylus 10 and the

advance ball 8 is mounted upon the frame of the unit directly alongside the recording stylus 10 and, of course, on the uncut side of the record.

5 The height of the advance ball is so chosen and adjusted that the difference between the height of the two is equal to the depth of cut as already stated. Consequently, when the unit is in the position shown in Fig. 1 and is 10 lowered upon the record, the recording stylus 10 will be forced into the record the correct distance. It cannot cut any further into the record because the engagement of the advance ball 8 with the record prevents such action.

15 While in the figures herein a cylindrical record has been shown, it will be understood that my invention is not limited to use with cylindrical records but is applicable to disc records also.

20 While I have not shown any specific form of electromagnetic apparatus, it will be understood that the arrangements shown and described in the foregoing application already referred to, may be utilized, or any 25 satisfactory reversible electro-magnetic or electro-static or electro-dynamic apparatus may be utilized which is capable of converting electric currents or potentials into mechanical vibrations and vice versa. Since 30 many of these are well known in the art, and form per se no part of this invention, they are not described in detail.

Also, the various arrangements of styli and arms shown and described in the foregoing 35 application may be utilized with this invention.

The unit is carried by arm 5 to which the unit is pivoted as at 12 so as to be rotatable and capable of being held in recording and 40 reproducing positions respectively as shown in Figs. 1 and 4. The lever arm 5 is pivoted as at point 6 and may be provided with a counter-balance 7 or a spring may be utilized to lessen the pressure on the record if desired.

45 It will be noted that if the advance ball is not in a line precisely at right angles to the record groove and passing through the recording stylus, the depth of cut will be changed as the diameter of the record 50 changes, due to a change of angle between the recorder and the record. In order to minimize this change the pivot about which the arm 5 swings should be placed in a line which is tangent to the surface of the average size 55 record as shown in Fig. 1. It will be noted with reference to Fig. 1 that R_2 and R_1 represent maximum and minimum record diameters. R_3 is the mean of diameters R_1 and R_2 and the pivot 6 is preferably mounted on 60 a line tangent to the surface of the record of mean diameter R_3 .

While I have shown and described certain preferred embodiments of my invention, it will be understood that modifications and 65 changes may be made without departing from

the spirit and scope thereof as will be understood by those skilled in the art.

I claim:

1. A combined electrical sound recorder and reproducer unit, comprising, in combination, a frame, a recording stylus carried by said frame, a reproducing stylus carried by said frame, reversible means for converting electric currents into mechanical vibrations associated with said styli, an advance ball 70 mounted on said frame, adjacent said recording stylus and on a line passing through the cutting face of said stylus and parallel to the line of advance of the stylus over the record, and means for supporting said unit in different positions on a record, in one of which said advance ball and said recording stylus engage the record, and in the other said reproducing stylus only engages said record.

2. A combined electrical sound recorder and reproducer unit, comprising, in combination, a frame, a recording stylus carried by said frame, a reproducing stylus carried by said frame, reversible means for converting electric currents into mechanical vibrations associated with said styli, an advance ball mounted on said frame, alongside said recording stylus, and means for selectively supporting said unit in different positions on a record, in one of which said advance ball 75 and said recording stylus engage said record, and in the other said reproducing stylus only engages said record.

3. A combined electrical sound recorder and reproducer unit comprising, in combination, a frame, a recording stylus carried by said frame, a reproducing stylus carried by said frame, reversible means for converting electric currents into mechanical vibrations associated with said styli, an advance ball 100 mounted on said frame alongside said recording stylus, an arm for supporting said unit in different positions on a record, in one of which said advance ball and said recording stylus engage said record, and in the other said reproducing stylus only engages said record, said arm being pivotally secured to a support at a point substantially on a line tangent to the record surface.

4. A combined electrical sound recorder and reproducer unit comprising, in combination, a frame, a recording stylus carried by said frame, a reproducing stylus carried by said frame, reversible means for converting electric currents into mechanical vibrations 105 associated with said styli, an advance ball mounted on said frame alongside said recording stylus in such position that a line joining the recording stylus and advance ball defines the line of advance of said stylus across the record, the height of said advance ball being less than the height of said stylus, whereby said advance ball does not engage said record until after said recording stylus has engaged said record, and 110

means for supporting said unit in different positions on said frame, in one of which said advance ball and said recording stylus engage said record and in the other of which said reproducing stylus only engages said record.

5. A combined electrical sound recorder and reproducer unit comprising, in combination, a frame, a recording stylus carried by said frame, a reproducing stylus carried by said frame, reversible means for converting electric currents into mechanical vibrations associated with said styli, an advance ball mounted on said frame alongside said recording stylus and in such position that a line joining the recording stylus and advance ball defines the line of advance of said stylus across the record, the height of said advance ball being less than the height of said recording stylus, whereby said advance ball does not engage said record until after said recording stylus is in contact therewith, said advance ball and said recording stylus being displaced from the center of said unit, and means for supporting said unit in different positions on a record, in one of which said recording stylus and advance ball engage said record, and in the other of which said reproducing stylus only engages said record.

30 6. A combined electrical sound recorder and reproducer unit comprising in combination, a frame, a recording stylus carried by said frame, a reproducing stylus carried by said frame, reversible means for converting electric currents into mechanical vibrations associated with said styli, an advance ball mounted on said frame alongside said recording stylus and on a line passing through said recording stylus and normal to the tangent to the record groove at the point of contact with the said recording stylus and of such height that said recording stylus engages said record before said advance ball, and means for supporting said unit in different positions on said record in one of which said recording stylus and advance ball engage said record, and in the other of which said reproducing stylus only engages said record.

7. A combined electrical sound recorder and reproducer unit comprising in combination, a frame, a recording stylus carried by said frame, a reproducing stylus carried by said frame, reversible means for converting electric currents into mechanical vibrations associated with said styli, an advance ball mounted on said frame alongside said recording stylus, and on a line passing through said recording stylus and normal to the tangent to the record groove at the point of contact with said recording stylus, and of such height that said recording stylus engages said record before said advance ball and means for supporting said unit and for locking said unit in either of two different positions, in one of which said recording stylus and ad-

vance ball engage said record, and in the other of which said reproducing stylus only engages said record.

8. A combined electrical sound recording and reproducing unit for cylindrical records, comprising, in combination, a frame, a recording stylus carried by said frame, a reproducing stylus carried by said frame, reversible means for converting electric currents into mechanical vibrations associated with said styli, an advance ball mounted on said frame adjacent said recording stylus and on a line passing through the cutting face of said stylus, and parallel to the line of axial advance of said stylus, an arm secured to said unit at one end, and having its other end pivotally secured to a support, at a point on a line tangent to the surface of a record in recording position.

This specification signed this 9th day of April, 1931.
